Ernest Stares

ATTORNEY.

UNITED STATES PATENT OFFICE.

FREDERICK F. FULTON, OF ST. LOUIS, MISSOURI, ASSIGNOR OF ONE-HALF TO CLAIRE W. FULTON, OF CHICAGO, ILLINOIS.

SKIRT-GAGE.

No. 826,417.

Specification of Letters Patent.

Patented July 17, 1906.

Application filed March 5, 1906. Serial No. 304,273.

To all whom it may concern:

Be it known that I, FREDERICK F. FULTON, a citizen of the United States, residing at St. Louis, State of Missouri, have invented certain new and useful Improvements in Skirt-Gages, of which the following is a full, clear, and exact description, reference being had to the accompanying drawings, forming a part hereof.

10 My invention has relation to improvements in skirt-gages; and it consists in the novel construction of gage more fully set forth in the specification and pointed out in the claims.

15 In the drawings, Figure 1 is a perspective view of the gage applied to a lady's skirt. Fig. 2 is a vertical section on line 2 2 of Fig. 3. Fig. 3 is a horizontal section on line 3 3 of Fig. 1, and Fig. 4 is a perspective showing the 20 sliding arm carrying the gage member or arm in an inverted position on the scale-rod.

The object of my invention is to construct a simple gage for adjusting ladies' skirts to proper lengths without the use of chalk-marks, one which is readily adjustable, one conforming readily to the contour of a skirt, one which will in no wise injure the skirt, and one possessing further and other advantages better apparent from a detailed description 30 of the invention, which is as follows:

Referring to the drawings, 1 represents a suitable base from which projects centrally a vertical scale-rod or standard 2, capped by an ornamental screw-knob 3, if desired. 35 Freely sliding along the scale-rod 2 is the socket 4 of a horizontal arm 5, whose outer end terminates in an upwardly-deflected portion 6. Formed with or secured to said portion 6 and flush with the upper face thereof 40 is a flat outwardly convexed or bowed gage member 7 of convenient length, the vertical depth (or width) of the said bowed member being such that its lower edge is disposed substantially in the horizontal plane of the 45 upper face of the socket 4, (slightly above said plane,) which serves as the index for the marks or divisions on the rod 2. The socket 4 is secured to the scale-rod at any adjusted position by a clamping-screw 8.

50 In the practical operation of the device the wearer of the skirt stands against the base 1, so as to bring the device inside the skirt 5. (The rod 2 is in the neighborhood of fifteen inches.) The skirt hangs over the curved

member 7, (previously adjusted vertically to a plane which shall mark the length of the skirt,) whereupon the skirt is folded inwardly over the gage member, the folded portion being secured by pins 9 to the main body of the skirt. The length of the member 7, measured along the arc of the horizontal circle which describes it, is approximately eight inches, so that the skirt can be folded in sections corresponding in length to such arc. The folded portion is then slipped off the said member, and other portions of the skirt are consecutively folded until the entire circumference of the skirt-bottom is gone over. The person wearing the skirt at the same time turns around the base 1 to facilitate the 70 passing of freshly-folded portions of the skirt along the gage member. To avoid accidental injury or puncturing of fine dress material by the free end of the member 7 in the event the wearer should swerve or turn in the opposite direction to that by which the folded portion is slipped off the said member, the curvature of the member is depended on, since it conforms approximately to the path which the skirt would take with the turning 75 of the person. The division-marks on the scale being referred to in the reading thereof to the upper face of the socket 4, it is for that reason that the lower edge of the gage member 7 is disposed substantially in the plane of 80 said upper face. Thus in Fig. 1 the mark "5" on the scale indicates that the lower edge of the member 7, which gages the skirt, is in the plane of the fifth main division-mark 85 on the scale.

The length of the arm 5 is such that by inverting it and slipping it back on the rod 2 the said arm reaches just beyond the edge of the base 1, allowing the deflected member 6 to overlap the base and bring the upper edge 95 of the gage member to the floor, if desired, so that with my present device the reversible character of the sliding members 5 6 7 permits a skirt to be taken up or gaged from *nil* to any vertical height. It will be seen that 100 there is no occasion to employ any crayon or chalk to mark the line which is to determine the length of the skirt.

Having described my invention, I claim—

1. In a skirt-gage, a vertical scale-rod, an 105 outwardly-projecting arm adjustable along said scale-rod, and an outwardly convexed or bowed gage member carried at the outer

end of said projecting arm, substantially as set forth.

2. In a skirt-gage, a vertical scale-rod, a horizontal arm having a socket adjustable along the rod, a terminal deflected portion at the outer end of the arm, and an outwardly convexed or bowed gage member carried by the deflected portion, substantially as set forth.
3. In a skirt-gage, a vertical scale-rod, a horizontal arm having a socket adjustable along the rod, a terminal deflected portion at the outer end of the arm, a flat outwardly

convexed or bowed gage member for the folding of the skirt, the lower edge of the gage member being disposed substantially in the plane of the upper face of the socket to which the divisions on the scale are referable, substantially as set forth.

In testimony whereof I affix my signature in presence of two witnesses.

FREDERICK F. FULTON.
